CLAIM

The ornamental design for an apertured foil for electric dry shavers, as shown and described.

DESCRIPTION

FIG. 1 is a front plan view of an apertured foil for electric dry shavers showing my design, the rear plan view being identical in appearance;

FIG. 2 is a top elevational view thereof, the bottom elevational view being identical in appearance; and,
FIG. 3 is a right side elevational view thereof, the left side being identical in appearance.

The rows of apertures shown are understood to repeat throughout the regions bounded by the broken lines on the drawing.

FIG. 3

FIG. 2

FIG. 1
